UTILITY BOX FLAG

Grant Arthur Roe, Middletown, N. Y.

Application December 1, 1943, Serial No. 512,439

2 Claims. (Cl. 232—35)

This invention relates to flags for utility boxes, mail boxes, milk boxes, or any box requiring a signal flag.

The object of the invention is to provide a signal flag which may be seen at a considerable distance; which may be set in an upright position to indicate that there is something in the box to be taken; which will automatically go down to a horizontal position when the door or lid of the box is opened; and which may be used to force the door or lid of the box open in the event such door or lid is frozen or rusted, or hard to open.

One form of the invention is illustrated in the accompanying drawing of a rural mail box, in which Figure 1 is a side view of the box with the signal flag in an upright position indicating that there is something in the box to be taken. Figure 2 is a side view of the box showing the flag being forced down to a horizontal position as the lid of the box is opened, or showing the lid of the box being forced open when pressure is used on the flag to move it from the upright position to the horizontal position. Figure 3 is a front view of the box showing the flag in the upright position. Figure 4 is a separate top view of angle plate 7.

In the above mentioned figures 1 is a vertical section of the box; 2 is the flag; 3 is the flagstaff; 4 is a pivot by which the flagstaff is fastened to the body of the box; 5 is the handle by which the lid is opened; 6 is the lid of the box; 7 is an angle plate fastened to the lid by rivets 8 and 9; 10 is a stopblock to hold the flagstaff in a horizontal position; 11 is a slot in the lower end of flagstaff 3; and 12 are pivots by which the lid is secured to the body of the box.

In the accompanying drawing flagstaff 3 is secured to box 1 by means of pivot 4 on which the flagstaff 3 may rotate. Figure 1 shows the lid closed and the flag in upright position with angle plate 7 comprising a projection 7a, engaging slot 11. As lid 6 is moved to open position by means of handle 5 the angle plate 7 moves with the lid, being secured to the lid by rivets 8 and 9, and being engaged in slot 11 it carries the lower end of flagstaff 3 with it causing the flagstaff 3 to rotate on pivot 4 and the flag to move toward a horizontal position as shown in Figure 2. The weight of the flag 2 then carries the flagstaff 3 on down against stopblock 10.

The reverse of this operation is also true. With the lid closed and the flag in upright position as shown in Figure 1, use pressure on flag 2 and move it toward a horizontal position. The flag-

staff 3 then rotates on pivot 4 and the lower end of the flagstaff 3 bears against angle plate 7, which is secured to the lid 6 by means of rivets 8 and 9, and the lid 6 is forced to open position as shown in Figure 2 without touching the handle 5.

It will therefore be readily seen that when the lid is opened in the usual way by handle 5 the flag is automatically forced down to a horizontal position and the additional operation of putting the flag down, as is necessary with the type of boxes and flags now in use, is entirely eliminated. When, because of ice, rust, etc., the lid can not be opened in the usual way with handle 5, the flag may then be used as a lever to force the lid open.

It will be noted from Figure 1 of the drawing that the notch 11 is formed at the lower end of the flagstaff below the pivot 4, so that, when the lid is closed, the projection 7a carried by the lid, the pivot 4 and the notch 11, as well as one of the pivots 12, are all in vertically substantial alinement. The flagstaff is, therefore, adapted to function as a straight lever of the first class. As such, it receives from or imparts to the projection 7a, a direct thrust when the lid is at or near its fully closed position. It is here that the maximum force is required to initiate pivotal movement of the lid on its pivots 12 or pivotal movement to the flagstaff on its pivot 4, as the case may be.

Having described my invention and illustrated its operation by means of the accompanying drawing; therefore,

I claim:

1. A receptacle body having a pivoted closure, a signal flag having a flagstaff pivoted intermediate its ends to the receptacle body for movement from vertical to horizontal position and vice versa and provided at its lower end with a flaring notch, a projection mounted on and carried by the closure below the pivot of the flagstaff and in a position to be straddled by the notch of the flagstaff when the lid is in closed position with the flagstaff vertical, said flagstaff pivot, notch and projection being at that time in substantial vertical alinement, whereby pressure applied to the flagstaff to move it from vertical to horizontal position will impart pivotal movement to the closure and pivotal movement of the closure from closed to open position will impart pivotal movement of the flagstaff in the direction of its horizontal position.

2. A receptacle body having a lid mounted for pivotal movement on horizontal pivots near the

bottom of the receptacle and provided with a projection on one side of said lid extending when the lid is closed to a point substantially vertically above one of the lid pivots, and a signal flag having a straight flagstaff movable from vertical to horizontal position on a pivot secured to the receptacle body vertically above the projection of the lid when the lid is closed, said flagstaff being provided at its lower end with a flaring

5 notch straddling the projection of the lid, whereby pressure applied to the flagstaff to move it from vertical to horizontal position will impart pivotal movement to the lid and pivotal movement of the lid from closed to open position will impart pivotal movement of the flagstaff in the direction of its horizontal position.

GRANT ARTHUR ROE.
